Patented Feb. 23, 1915.

UNITED STATES PATENT OFFICE.

JOSEPH SEHOLM AND ERIC W. MELLIN, OF BLOOMFIELD, NEW JERSEY.

DEVICE FOR APPLYING BLACKING AND THE LIKE.

1,129,524.

Specification of Letters Patent. Patented Feb. 23, 1915.

Application filed December 23, 1913. Serial No. 808,496.

To all whom it may concern:

Be it known that we, JOSEPH SEHOLM, a citizen of the United States, and ERIC W. MELLIN, a subject of the King of Sweden, 5 and residents of Bloomfield, county of Essex, and State of New Jersey, have invented certain new and useful Improvements in Devices for Applying Blacking and the like, of which the following is a 10 specification.

This invention relates to an improved device for applying blacking or similar pasty substances by means of a suitable dauber, such as a brush or a pad, and is particularly adapted to provide an applying device of this type which has a means for holding a receptacle for the blacking or similar material, the holder being preferably made to receive the ordinary tin box in which 20 the blacking is sold.

The invention is also designed to provide a dauber which has means for attaching it to a handle of the device so that when the handle is operated to move the box of blacking, the brush is moved so as to engage the blacking in the box, and when released the brush is again returned to its normal position and is ready for use with the blacking on it. The normal position of the box is 25 such that it is closed by the back of the brush and the blacking does not have a chance to dry out, which it very often does when it is simply provided with a loose cover. The device is so constructed that 30 when the handle is operated, which is usually and preferably done by squeezing it, the box of blacking is opened and the brush is turned to be opposite the open side of the box. By a slight release of the handle the dauber or brush and the opening 35 of the box are moved toward each other so as to insure the depositing of some material from the box onto the brush. Another slight compression on the handle separates the box 40 and the brush sufficiently to permit the brush to clear the box and revolve to its normal position, and a full release of the handle then permits the box to stop in its place and it is closed. In this case while a 45 box of blacking is referred to to make the description clear, it will be understood that different kinds of receptacles containing different kinds of materials can be used in this device, and further, that any kind of a 50 dauber can be used, whether it is in the

nature of a brush or a pad or similar element.

The invention is illustrated in the accompanying drawing, in which—

Figure 1 is a perspective view of the device in its normal position showing the box closed and the dauber ready for use. Fig. 2 is a top view of the construction shown in Fig. 1, and Fig. 3 is a section on line 3, 3, in Fig. 2. Fig. 4 is a side view of the 60 dauber end of the handle, showing the dauber and the brush in their normal positions in full lines, and showing, in dotted lines, the box raised to its open position.

Numerous forms can be made of this device, and the particular form of handle and holding coils and similar parts can be made in different ways, but for the purpose of clearly setting forth this invention, we have embodied one type in the drawing. 70 The embodiment shown consists of a handle which is made up of strands that can be moved toward each other, when in the hand, by squeezing them together. One of these strands 10 is provided with a neck 75 11 which extends upwardly and is then bent into a ring 12 which forms a spring ring for holding a box 13 which, in the drawing, is shown as an ordinary blacking box which is arranged in the ring 12 with 80 its top downward, the purpose of which will be described hereinafter. The strand 10 is bent into a coil 14 to give a spring action to the strand 10 and also to the strand 15 which is fastened at 16^a to a strand 17, 85 90 these two upper strands being slightly divergent and so arranged that the strand 10 passes between them, since the strands 15 and 17 are bent down at 16 and 18, respectively, and then forward at 19 and 20 to 95 form the arms 21 and 22, which arms support the dauber 36 which, in the form shown, is illustrated as a brush. The downwardly bent part of one of the strands is slightly curved. In the drawing the strand 100 18 is shown thus curved at 23 to bring the top portions of the parts 16 and 18 closer together than the bottom portions, the purpose of which will be described hereinafter. The brush is mounted between the arms 21 105 and 22 so that it can rotate therein. One arm 21 is bent into a loop 23^a through which a screw 24 passes, which screw is fastened to the brush, the other arm 22 being flattened at its end, as at 25, this flattened por- 110

tion passing through a slot 26 in the side of the brush, and being bent into a half turn 27 so that when the arm 22 moves outward, the brush is caused to turn by reason of the twisted portion 27 passing through the slot 26.

A suitable clip slides on the downwardly bent portions 16 and 18 of the upper strands 15 and 17 of the handle, the clip being bent 10 into a loop 28 around one of the downwardly depending portions of the strands 15 and 17. In the drawing this coil is shown as encircling the downwardly extending portion 18, and then extending across at 29 to 15 form a stop, and then into a loop 30 around the portion 16, the clip then extending downward as at 31 to form a connection between the loop 30 and the lower loop 32, the wire then extending across to form a lower stop 20 33. The strand 10, it will be noted, extends forward between the upper stop 29 and the lower stop 33. The dauber has a back 35 which acts as a closure for the open side of the box or receptacle in which blacking is held, and a tight joint to prevent drying out 25 of the blacking is provided for by a sheet or ring 34, which ring is preferably made of elastic or other compressible material, such as rubber, felt or the like.

30 The operation of the device is as follows: An ordinary box of blacking 13 is placed in the ring 12 and held therein by the spring pressure of the ring, and is inverted so that its edge bears on the ring or pad 34 so that 35 the blacking is kept from contact with anything and also from drying out. When the device is to be used, the handle is grasped and squeezed. This swings the arm 21 from the position shown in full lines in Fig. 4 to 40 the position shown in dotted lines in said figure. As the strand 10 passes upward and the strands 15 and 17 pass downward, the strand 10 engages the upper stop 29 of the clip and the clip then slides upward with 45 the strand 10, and when the box is nearly in its uppermost position, the loop 28 engages the curved portion 23 of the strand 18, which causes an outward movement of the portion 18 and its arm 22, this outward swinging 50 of the arm causing the twisted portion 27 to pass out through the slot 26, and the dauber or brush is turned over with its daubing surface opposite the open side of the box 13. When the brush is in this inverted 55 position it is necessary to allow the box to be settled down on the brush so as to insure the placing of some blacking on the brush. This is done by slightly releasing the handle, and the spring action of the loop 14 forces 60 the strands so that the box 13 settles down on the inverted brush, and at the same time pulls the clip down so that the tendency of the downwardly extending portion 18 on the arm 22 is to move inward to return the brush 65 to its normal position, but this is prevented by

the engagement of the brush with the blacking in the box, as the edge or rim of the box will engage the brush, especially when there is only a little blacking left in the box. In other words, the stop 29 and the loop 28 ride down beyond the curved portion 23 so that the brush has a normal tendency to resume its position as soon as it is released from the box. This releasing is accomplished by another slight squeezing of the handle in which the strand 10 travels upward from its engagement with the lower stop 33, and having a little play within the clip, it releases the brush by the time the strand 10 engages the upper stop 29, and the brush turns over, this of course taking place very quickly, and the handle is then in position to be used as the handle of the dauber in applying the blacking to whatever surface is to be blackened or polished. It takes but 85 a slight and simple movement to operate the device, since when it is taken hold of by the hand, it is tightly squeezed, slightly released, then slightly squeezed again, which second squeezing permits the turning of the brush to its normal position, and then the handle can be fully released and used as the handle of the dauber.

This device permits the blacking or polishing of a surface without necessarily soiling the hands or clothing, as it is not necessary to handle the box of blacking, this being always ready for use and at the same time always closed, which permits the economical use of blacking.

It will be evident that the operation of the device will be more easy if the loop 28 is made to fit loosely on the outside of the downwardly extending portion 18, that is, the loop can be made rather large, but so 105 disposed that it bears on the inner edge of the portion 18 rather than on the outer edge.

Having thus described our invention, what we claim is:—

1. A device for applying pasty substances 110 comprising a box-holding strand to normally support a receptacle bottom up, a dauber-holding strand, said strands being adapted to be moved toward and from each other and to form a handle, and means on said dauber-holding strand for swinging the dauber when the strands are operated.

2. A device for applying pasty substances comprising a box-holding strand formed to hold a receptacle in inverted position, a 120 dauber-holding strand, the strands being substantially parallel and connected so as to form a handle, the strands being crossed and capable of movement toward and from each other, a dauber on the dauber-holding strand and normally pressed against a receptacle so as to close it, and means on the dauber-holding strand for swinging the dauber when the strands are operated.

3. A device for applying pasty substances 130

- which comprises a handle, means on the handle for supporting an inverted receptacle, a brush mounted on the handle with its back acting as a closure for the inverted receptacle, and means for inverting the brush and raising the receptacle in unison. 5
4. A device for applying pasty substances which comprises a compressible handle, means on the compressible handle for supporting an inverted receptacle, a brush mounted on the handle with its back acting as a closure for the inverted receptacle, the handle raising the receptacle holder when the handle is compressed, and means connecting said raising means and the brush for inverting the brush when the holder is raised. 10
5. In a device for applying pasty substances, a handle consisting of strands that diverge into spring arms, a brush mounted between the spring arms and adapted to be rotated when the arms are moving laterally, and means on the handle for so moving the arms. 15
- 25 6. A device for applying pasty substances comprising a handle having a forwardly projecting strand, means on the end of the strand for holding an inverted receptacle, divergent strands having arms thereon, the arms being adapted to be sprung apart, means actuated by the strand carrying the receptacle for spreading the arms, a dauber supported between the spring arms, and co-acting means on the dauber and at least one 30 of the arms for inverting the dauber when the arms are spread.
7. In a device for applying pasty substances, a handle consisting of a lower strand, means on the end of the lower strand 40 for holding an inverted box of pasty substance, a loop at the rear end of the lower strand, a pair of upper strands connected to the loop and having downwardly curved extensions between which the lower strand of
- the handle passes, arms on the extensions, a 45 dauber between the arms, a clip sliding on the downwardly extending portions of the upper strands, at least one of the downwardly extending portions being adapted to be actuated by the movement of the clip to 50 move the arms away from and toward each other, the clip being constructed so as to be engaged by the lower strand on its vertical movements, and a flattened and twisted portion at the end of at least one of the 55 arms entering the dauber, the dauber having a slot through which said flattened and twisted portion is adapted to pass to cause the inverting of the dauber. 55
8. In a device for applying pasty substances, a handle, spring arms on the handle, the arms having a lateral movement relative to each other, a brush mounted between the arms, the brush and arms having co-acting means for revolving the brush 60 when the arms are moved laterally, and means for so moving the arms. 65
9. In a device for applying pasty substances, a handle, spring arms on the handle, the arms having a lateral movement 70 relative to each other, a brush mounted between the arms, the brush and arms having co-acting means for revolving the brush when the arms are moved laterally, means for so moving the arms, a vertically movable holder for an inverted receptacle, and means actuated from the handle for automatically raising the holder when the arms are moved for placing the receptacle in the path of travel of the brush. 75
- 80
- In testimony that we claim the foregoing, we have hereto set our hands, this 22nd day of November 1913.
